(57) CLAIM

The ornamental design for a dutch oven lid, as shown and described.

DESCRIPTION

FIG. 1 shows a perspective view of a dutch oven lid according to a first embodiment of the present invention.

FIG. 2 shows a front view of the dutch oven lid of FIG. 1, the rear view being the same.

FIG. 3 shows a right side view of the dutch oven lid of FIG. 1, the left side view being the same.

FIG. 4 shows a top view of the dutch oven lid of FIG. 1; and, FIG. 5 shows a bottom view of the dutch oven lid of FIG. 1.

The broken lines of the dutch oven lid are for illustrative purposes only, and form no part of the claimed design.
